SNAP VALVE

Frank A. Gauger, Milwaukee, Wis.

Application March 7, 1932, Serial No. 597,124

5 Claims. (Cl. 137—139)

Objects of this invention are to provide a novel form of automatic valve which is so made that it snaps fully open or fully closed, and is at all times leak proof where the operating means passes through the casing although freely and easily operated, and which is devoid of packing or stuffing boxes.

Further objects are to provide a valve of the above outlined type which is thermostatically controlled in a manner to cause the operation of the valve at the initial portion of the movement of the thermostatic member or device, for either opening or closing motion, without waiting for the thermostatic member to execute its full stroke or movement.

Further objects are to provide a novel construction in which the operative connection between the thermostatic member and the valve involves the use of a friction clutch device, so that the thermostatic member may operate the valve at the initial portion of its stroke and may slip along during the remainder of its stroke after the valve has either opened or closed, thereby preventing warping or straining of any of the parts although providing a thermostatically controlled valve which is very quickly responsive.

Embodiments of the invention are shown in the accompanying drawings in which:—

Figure 1 is a fragmentary plan view somewhat diagrammatically shown, illustrating the relative position of the device on the stove and showing one application of the invention.

Figure 2 is a sectional view on the line 2—2 of Figure 1.

Figure 3 is a sectional view approximately on the line 3—3 of Figure 1.

Figure 4 is a sectional view through the valve casing, said view corresponding to a section on the line 4—4 of Figure 5.

Figure 5 is a view of the valve structure with the cover plate removed and with parts broken away.

Figure 6 is a fragmentary detail view showing a modified form of construction.

Referring to the drawings, it will be seen that the device has been shown as applied to a gas stove provided with a main pilot 1, top burners 2, and an oven burner 3. The oven burner is provided with a projecting portion 4 adjacent the opening 5 through the oven wall 6.

All of the burners and pilots of the stove are supplied from the manifold 7. The oven burner and its associated auxiliary pilot hereinafter described are both supplied through the valve 8

which controls the flow of gas from the manifold 7 to the pipe 9.

The pipe 9 extends to the automatic thermostatically controlled valve indicated generally by the reference character 10, see Figures 1 and 2, and from this valve a pipe 11 leads to the oven burner.

It is to be noted from Figure 2 that a by-pass pipe 12 is provided and extends from the pipe 9 to the mixing tube 13 of the auxiliary pilot. 10

From Figure 3 it will be seen that this auxiliary pilot has the mixing tube 13 screwed into a casting 14 which is provided with a lateral extension 15 having a plurality of holes 16 and projecting through the aperture 5, see Figure 1, into proximity to the member 4. The relative vertical position of the parts is shown in Figure 3. 15

It is to be noted that the casting 14 of the auxiliary pilot is provided with an extension having an annular threaded portion 17 upon which 20 an adjustable sleeve 18 is screwed to thereby limit the entrance of secondary air into a flash back tube 19 fitted within the annular extension 17, such flash back tube being hereinafter described in greater detail. The casting 14 is provided with a cluster burner immediately below the adjustable sleeve 18, the holes of such burner being indicated by the reference character 20 in Figure 3. This cluster burner may be of any suitable type, an additional form of cluster burner 30 being shown in Figure 6 which will be described later. 25

The casting 14 is provided with an arm 21, see Figure 2, to which the pin 22 is rigidly secured. This pin carries the thermostatic member 23 and 35 is adapted to be locked in any desired adjusted position by means of the nut 24, see Figure 3.

It is to be noted from Figure 2 that the burner 15 of the auxiliary pilot is provided with a plurality of openings 25 which cause a plurality of 40 flames to play upon the thermostatic member 23 whenever such auxiliary pilot is lighted and thereby heat the major portion of this thermostatic member and secure a pronounced and rapid response, causing the thermostatic member to 45 move within an extremely brief period after the lighting or extinguishing of the auxiliary pilot.

The thermostatic member 23 carries a fitting 26 adjacent its free end which is provided with a pair of bowed spring jaws or friction jaws 27 50 most clearly shown in Figure 5. These spring jaws 27 frictionally grip an extended portion 28 of a valve controlling arm 29, suitable adjustable stops being provided as indicated in Figure 2.

The automatic valve 10 is carried in any suit- 55

able manner as by means of a plate 30 secured at one end to the casting 14, as may be seen from Figure 2.

The valve arm 29 is rigidly secured to the rock shaft 31, see Figure 5. This rock shaft has a reduced portion which extends through the wall of the casing of the valve and is provided with a ground beveled surface or collar 32 integral therewith and seated upon a valve seat formed in the casing of the valve, as very clearly shown in Figure 5, to thereby maintain a gas tight joint without any packing whatsoever. The other end of the shaft 31 is beveled and a follower 33 is spring pressed against such beveled end to maintain the gas tight fit between the ground flange or collar 32 and the casing.

An arm 34 is rigidly secured to the rock shaft 31 and is provided with a central cut out portion 35 within which a bowed spring 36 is positioned. The ends of the bowed spring are carried within members 37 provided with V-shaped slots, as shown in Figure 4, and provided with forked ends which interfit with corresponding portions of the arm 34. The bowed spring is approximately centrally slotted, as indicated at 38, and fits loosely over a reduced portion 39 formed on the stem of the valve 40, the valve 40 cooperating with a fitting 41 provided with a valve seat and having an extension 42 guided by the casing 30 of the valve, as shown in Figure 4.

The bowed spring 36 is slotted adjacent one end and oppositely bowed loops 43 are formed from the two half strips of the spring produced by this slit, such slit being indicated at 44 in Figure 5.

When the rock arm 31 is rocked in a counter-clockwise direction, as viewed in Figure 4, the spring 36 will be tensioned and will finally snap suddenly upwardly or, in other words, will suddenly bow upwardly, thereby raising the valve 40 as viewed in Figure 4 and opening such valve with a quick motion. A reverse rocking action of the rock shaft 31 will cause the spring to suddenly bow downwardly, as shown in Figure 4, thereby closing the valve with a snap action.

The friction obtained between the spring jaws 27 carried by the thermostatic member and the portion 28 of the rock arm 29 previously described insures the operation of the valve during the initial motion from either position of the thermostatic member. This friction clutch device permits the thermostatic member to complete its entire stroke without producing straining of any of the parts, as the frictional slip joint permits the spring jaws 37 to slip over the member 27 to accommodate the additional movement of the thermostatic member.

However, a very pronounced beneficial result is obtained by this construction, for it will be noted that the initial movement of the thermostatic member actuates the valve and consequently a very quick response is obtained, as the thermostatic member does not have to complete its entire stroke in either direction to either open or close the valve.

Further, by combining this construction with that of the snap acting valve an extremely quick and positive response is obtained during the initial portion of the stroke of the thermostatic member in either direction, thereby fully opening or fully closing the valve during this initial portion of the stroke of the thermostatic member.

Returning to the flash back tube 19, attention is called to the fact that this tube extends upwardly and thereafter laterally to adjacent the

main pilot 1, as may be seen from Figures 1 and 3. The flash back tube 19 is provided with a series of apertures 45 on the underside of the horizontal portion thereof and on the corresponding side of the vertical portion. These apertures provide for the additional admission of secondary air. The admission of secondary air at the charging point of this tube is adjustable by means of the adjustable sleeve 18, and also is limited not only by this sleeve but by the use of 10 the cluster burner immediately below the sleeve. The cluster burner produces a body of mixture substantially conforming to the interior contour of the adjacent portion of the flash back structure.

In other words, the cluster burner, which will 15 be more fully described in connection with Figure 6, produces a wall of gas, or in other words, a wall or mixture or a cylindrical body of mixture which limits the entrance of secondary air and consequently provides for a reasonable rate 20 of travel of the mixture through the flash back tube 19, thereby allowing the flame which flashes back to be readily propagated at a rate in excess of the upwardly and outwardly traveling rate of 25 the mixture.

It is believed that a consideration of Figure 6 at this point will materially aid in the understanding of the invention. In this figure the casting 14' corresponds to that previously described and constitutes the auxiliary pilot 15' 30 corresponding to the portion 15 of Figure 3. However, a cluster burner tip or fitting 46 is inset below the upper level of the auxiliary pilot and is provided with a plurality of apertures 47 so as to insure the formation of a cylindrical or 35 other shaped body of mixture which substantially fills the lower end of the flash back tube or corresponding portion of the structure. In the form shown in Figure 6, the casting 14' is provided with an annular portion 17' which may 40 terminate sufficiently close to the auxiliary pilot face to avoid the necessity of using an adjustable sleeve 18, although it is to be distinctly understood that the adjustable sleeve may or may not be used with either form of the invention. Also, 45 if desired, an individual fitting corresponding to the fitting 46 may be employed with the structure as illustrated in Figure 3.

Returning a moment to Figure 6, it will be noted that the cluster burner or fitting 46 is 50 located in a plane below the upper face of the auxiliary pilot so that if there is a pressure wave from any source whatsoever, it cannot snuff out the cluster burner. If desired, an additional aperture 48 may be provided through the casting 55 14', as shown in Figure 6, for the admission of secondary air.

In operating the device, the valve 8 is opened and gas passes to the auxiliary pilot. The cluster burner fills the tube 19 with a charging 60 mixture which may be comparatively rich and which may be diluted to the proper amount by the admission of secondary air along the length of the tube through the apertures 45, see Figure 3. This mixture is ignited by the main pilot 1 65 and the flame flashes back and lights the auxiliary pilot. The thermostatic member 23 heated by the several small flames from the apertures 25 is substantially immediately bowed and snaps the oven valve into open position 70 during the initial portion of the stroke of the thermostatic member. The auxiliary pilot lights the oven burner and thus an automatic operation is secured with absolute protection against the supplying of the oven burner with gas if the 75

auxiliary pilot should fail for any reason whatsoever.

It will be seen that this invention enables an oven burner which is located at a point remote from and in a plane below that of the main pilot to be lighted from the main pilot with the utmost ease and certainty and in an extremely brief interval of time.

Further, it will be seen that an automatic valve has been provided which is thermostatically operated to completely open or completely close during the initial operation of the stroke of the thermostatic member.

It will be seen further that the device is extremely simple, has relatively few parts, and that it is substantially fool proof in its operation and requires no thought on the part of the operator.

The expression "ground joint" as used in the claims is to be understood as covering a joint whether a ground joint, or a machine joint, or any other type of joint of this general order.

I claim:

1. A valve construction comprising a valve seat, a valve cooperating with said seat, a rock shaft spaced laterally from said valve, a rock arm carried by said rock shaft, and a bowed spring carried by said rock arm and operatively connected with said valve adjacent the middle of said bowed spring, said bowed spring having compensating means adjacent one end of said bowed spring, and said rock arm being movable past the dead center position of said bowed spring, whereby a quick opening and quick closing of said valve is provided when said rock arm passes from side to side of the dead center position of said bowed spring.

2. A valve construction comprising a valve seat, a valve cooperating with said seat, a rock shaft spaced laterally from said valve, a rock arm carried by said rock shaft, and a bowed spring carried by said rock arm and operatively connected with said valve adjacent the middle of said bowed spring, said bowed spring having oppositely directed loops forming compensating means adjacent one end of said bowed spring, and said rock arm being movable past the dead center position of said bowed spring, whereby a

quick opening and quick closing of said valve is provided when said rock arm passes from side to side of the dead center position of said bowed spring.

3. A valve construction comprising a valve seat, a valve cooperating with said seat, a rock shaft spaced laterally from said valve, a rock arm carried by said rock shaft, a bowed spring carried by said rock arm and operatively connected with said valve adjacent the middle of said bowed spring, said bowed spring having compensating means adjacent one end of said bowed spring, and said rock arm being movable past the dead center position of said bowed spring, whereby a quick opening and quick closing of said valve is provided when said rock arm passes from side to side of the dead center position of said bowed spring, said valve having a stem projecting beyond said bowed spring, and guiding means for the projecting portion of said stem for guiding said valve for rectilinear motion.

4. A quick motion valve construction comprising a valve seat, a valve cooperating with said valve seat, a rock shaft spaced laterally from said valve, a rock arm carried by said rock shaft, said valve having a valve stem provided with a reduced portion, and a bowed spring carried at opposite ends by said rock arm and having an aperture adjacent the middle of said bowed spring loosely receiving the reduced portion of said valve stem.

5. A quick motion valve construction comprising a valve seat, a valve cooperating with said valve seat, a rock shaft spaced laterally from said valve, a rock arm carried by said rock shaft, said valve having a valve stem provided with a reduced portion, guiding means for said stem for guiding said valve for rectilinear motion, and a bowed spring carried at opposite ends by said rock arm and having an elongated aperture adjacent the middle of said bowed spring loosely receiving the reduced portion of said valve stem, said bowed spring having compensating means adjacent one end thereof.

45

FRANK A. GAUGER.
